MACHINE FOR ATTACHING ARTIFICIAL
STEMS TO BLOSSOMSCharles M. Andersen, Los Angeles, Calif., assignor
to Floyd R. Honn, Arcadia, Calif.

Application September 5, 1950, Serial No. 183,232

9 Claims. (Cl. 41—2)

1

My invention relates to a machine for attaching artificial stems to blossoms.

In providing certain blossoms with wires to replace their natural stems, or in addition to their stems, to aid in making up corsages or in wiring the blossoms into floral arrangement, use is made of florist's wire of relatively soft metal to enable the wire to be manipulated easily without damaging the blossoms.

When it is desired to push the wire through the relatively hard calyx of the blossoms an operator has to work with care to avoid bending the tip of the wire or damaging the blossom and as a result the work is slowed down, particularly when handling flowers such as roses which have a dense hard calyx.

It is an object of my invention to provide a machine which enables an operator to push florist's wire through the lower ends of flowers with ease and rapidity.

A further object of my invention is to provide a machine of the kind described which is arranged so that the whole operative cycle of the machine is accomplished by a single turn of a crank which the operator manipulates with one hand, using the other hand to position and remove the flowers or blossoms operated on by the machine.

Another object of my invention is to provide a machine of the kind described which is simply arranged and constructed so that the soft wire used is accurately guided and is provided with means to prevent incorrect operation of the machine which might result in snarling of the wire and stoppage of the device.

Still another object of my invention is to provide a device of the kind described which is strongly constructed so that no interruption of wiring operations is experienced due to the necessity of replacing or repairing parts, this feature is important since florists are usually required to work rapidly when providing large scale floral arrangements due to the necessity of avoiding loss of freshness of the flowers which wither rapidly when deprived of their natural stems.

Another object is to provide, in a machine of the above stated kind a means for manually causing a momentary interruption of the wire feed mechanism while the other parts of the machine continue to operate, so as to shorten the cut off lengths of wire, when it is desired to provide shorter pieces of wire for artificial stems or other purposes, as desired by the florist.

Still further objects and features of my invention will hereinafter appear from the following

2

description read together with the accompanying drawings which illustrate an embodiment now in operation and at present considered preferable by me.

In the drawings:

Fig. 1 is a side elevation of the device showing the relation of parts at the completion of an operative cycle.

Fig. 2 is a front elevation of the device looking at the right end of Fig. 1.

Fig. 3 is a fragmentary top plan view, parts being broken away to disclose interior construction. A released blossom is indicated in dotted lines in the view.

Fig. 4 is a fragmentary elevational view looking at the side of the device opposite to that shown in Fig. 1, with part of the enclosing door broken away to show a portion of the inner structure in full lines.

Fig. 5 is a cross section on line 5—5 of Fig. 4, drawn on a larger scale.

Fig. 6 is a fragmentary cross section on line 6—6 of Fig. 4, drawn on a larger scale.

Fig. 7 is a detail perspective view showing in a detached manner one of the friction wire feeding roller per se in which a segment is cut away, and includes the mounting means for said roller. In this view the scale is enlarged.

Fig. 8 is a detail side view, drawn on a larger scale, of the wire guiding and supporting means and associated parts securable to the front of the device, parts being sectioned to show their interior arrangement.

Fig. 9 is an end view of the parts shown in Fig. 8, as indicated by the arrows 9—9 in Fig. 8.

Fig. 10 is an end view of the parts shown in Fig. 8, as indicated by the arrows 10—10 in Fig. 8, extreme operating positions of the wire shearing member being indicated in full and in dotted lines.

Fig. 11 is a side elevation drawn on a larger scale of a gravity operated detent shown in Fig. 1, part of the detent being broken away and part sectioned to show its interior arrangement.

Fig. 12 is a side elevation of the crank and associated mechanism operated thereby. In this view the structures shown are portrayed in five different positions which progressively illustrate operative steps thereof.

Fig. 13 is a fragmentary cross section on line 13—13 of Fig. 8 wherein the wire shearing member is shown in inoperative position in full lines and in the operative position in dotted lines.

Referring now to Figs. 1, 2, 3 and 4, the numeral 20 indicates generally the frame or hous-

ing of the device which provides a mounting means upon which nearly all of the mechanism of the device is directly secured. In the embodiment herein described and illustrated the frame is formed as a box open on one side and fitted with a hinged door 21 closing the open side. Hinges for the door are indicated at 21a and a knob for opening the door is indicated at 21b.

The exterior elements of the operating mechanism are mounted on the closed side wall 22 of the frame and on its front end wall 23.

Within the housing the supply of wire to be extended is wound on a spool 24 rotatably mounted on a shaft 25 having a threaded end screwed into a threaded hole in side wall 22 of the frame. Any suitable means may be provided to hold the spool from overrunning the wire being drawn therefrom, as for example strips of heavy felt 26 pressed between the wire loaded spool and the adjacent end of the frame.

The wire 27 is led from the spool 24 through a guide nipple 28 mounted in an inwardly projecting boss 29 on the side wall 22 and is pulled forward by milled feed rollers 30, 31 which grip the wire between them.

The roller 30 (Fig. 7) is mounted to rotate freely with a gear later to be described on a shaft 32 extending across an opening 32a in a small frame 33, said frame being pivotally mounted on a pin 35 carried by a boss 36 (Fig. 6), said boss extending inwardly from the side wall 22. Said frame 33 is provided in its forward end portion with a bore 38 to receive said pin 35. A rearward extension 37 of the frame is provided with a recess 38 in which is located the lower end of a small coil spring 39 under compression, the opposite end of the spring being located in a partially threaded bore 40 in a boss projecting inwardly from the top of the frame, and bearing against the lower end of a set screw 41 screwing into the bore 40, the force exerted by the spring being controlled by the adjustment of the set screw 41.

The milled roller 30 is carried concentrically by one end portion of a gear 42 which meshes with an intermediate gear 43 which similarly carries the roller 31, said intermediate gear being mounted for rotation on a stud 44 screwed into an inwardly projecting boss 45 on the side wall 22.

The knurled rollers 30 and 31 are rotated through the medium of a power transmission gear 46 mounted on a stud 47 secured in a boss 48 extending inwardly from the side wall 22, said gear 46 meshing with the aforementioned gear 43.

Gear 46 is, in turn, rotated by a large driving gear 48a secured to a shaft 49 mounted in a bore in an inwardly extending bearing boss 50 of the wall 22, a bearing sleeve 51 being provided for the shaft.

An operating crank 52 is secured to a projecting end portion of the shaft 49 and is spaced from the outer face of the side wall 22 to allow parts later described to be mounted on said outer face out of the path of travel of the crank 52. The crank is provided with an operating handle 53 secured to the crank by a threaded stem 54.

Wire 27 after passing between said feed rollers 30, 31 is threaded through a second guide nipple 55 mounted in a boss 56 projecting inwardly from the front wall of the case, and then through a hole drilled through a hardened steel bushing 57 mounted in a counter-bored portion at the forward end of the bore in which the guide nipple 55 is mounted. It is to be noted that the holes or

bore drilled through bushing 57 and guide nipples 55 and 28 are aligned on an axis which extends substantially centrally and longitudinally of the frame 20 of the machine. On the forward wall 23 of the frame an exterior wire guiding and supporting fitting generally indicated at 58 (Fig. 8) is secured. Said fitting 58 comprises a small housing 59 attached to the upper part of the front wall of the frame by machine screws 60. A vertical slot 61 is provided through the side wall of the housing 59 on the same side as the closed side wall 22 of the housing 20. Housing 59 is formed with a central forwardly projecting frusto-conical, outwardly tapered extension 59a in which the rearward end of a wire guiding tube 62 is secured by set screws 63. Said extension is laterally offset from the center line of the frame, as clearly indicated in Fig. 3. Said tube 62 is provided with a longitudinal slot 64 (Figs. 8 and 10), this slot being aligned with a horizontal slot 64a in fitting 58, the latter slot being shown in Figs. 4 and 10.

A rod 65 is rockably mounted in the tube 62 and has a close fit therein. The outer end of this rod terminates even with the end of the tube, but the inner end of the rod projects into the housing 59 and abuts against the forward face of the hardened steel bushing 57. The inner end of the rod 65 is held in position in the housing 59 by a plate 66 (Fig. 8) having a hole into which the end of said rod 65 is fitted, said rod 65 being secured in any suitable manner to the plate 66. This rod is provided with a longitudinally extending groove 67 in its periphery which, before and during operation of the device to project a length of wire, is aligned with the interior of the hardened steel bushing 57, and is out of alignment with the slots 64 and 64a in the tube 62 and fitting 58 respectively. Since the axis of the rod is offset from the axis of the hole through the bushing rotation of the rod, which is effected at the end of the wire feeding operation of the device, will cause the wire to be sheared off at the face of the bushing 57, the slot 67 in the rod 65 being rotated into line with the slot 64 in the tube 62 to enable the sheared off length of wire to move out sideways from the slot 67 in the rod and through the slots in the tube 62 and fitting 58.

A groove 71 is cut across the face of plate 66 and an actuating arm 72 is secured in the groove by a screw 73, the end of the arm extending outwardly through slot 61 in the housing or fitting 58. A tension spring 74 acts to normally hold the edge of arm 72 against the lower end of the slot 61 with the groove 71 in the rod 65 in alignment with the hole through the hardened steel bushing 57 in which position the open side of the groove 71 is closed by the wall of the tube 62.

The arm 72 is moved upward at the termination of each operation of the device to rotate the rod 65 about its axis to shear off the length of wire resting in groove 71 from the length of wire drawn from the wire spool and passed into the hardened steel bushing 57, and to bring groove 71 into alignment with the slot 64 in tube 62, by operating means mounted on the exterior of the frame 20 and tube 62 and which will now be described.

Referring to Figs. 1 and 2 crank 52 is provided with an inwardly projecting pin 75 mounted in a hole drilled through the crank, so that the end of the pin is closely adjacent the side wall 22 of the frame 20.

A cranked lever 76 is pivoted on a screw 77 screwed into a threaded hole drilled through the

wall of the case and into an inwardly projecting boss on the inside of the frame. The free end 76a of lever 76 is adapted to engage against the underside of the portion of arm 72 projecting through slot 61 of housing 59. Lever 76 is swung upwardly by the engagement of pin 75 against the lower side of the lever, pin 75 being positioned so that it may pass beyond the outer angle of the cranked lever when the latter has moved arm 72 to its uppermost position. When not resting on pin 75, the downward movement of the lever is arrested by a stop 78 projecting from the face of the frame 20 and provided by the end of a screw screwed into the side wall 22 of frame 20.

Rotation of the crank 52 is effected in a clockwise direction and reverse rotation of the crank is prevented by means later described.

The tension spring 68 is secured at its lower end by the head of a machine screw 80 screwed into the side wall 22 and the upper end of said spring is engaged in a hole 80a drilled in the end of the arm 72 projecting from the housing 59, the spring normally holds arm 72 in lowered position and lever 76, which engages under the projecting end of arm 72, is held in position so that the pin 75 on the crank will strike the lever adjacent its angled portion as the crank nears the end of its rotation in each operative movement.

In order to prevent inadvertent reverse rotation of the crank 52 either when about to shear the wire or after termination of an operation and thus to prevent the wire from being drawn back through the drilled bushing 57 and forward guide nipple 55, a detent 80 is provided pivotally mounted on a pin 81 secured in side wall 22 of the frame. The detent is provided on its lower edge with a sloped shoulder having a holding face 82, and the end of the detent acts as a second holding face 83. The detent is held by a pin 83a projecting from the frame in position to be engaged by a pin 84 projecting inwardly from the crank 52.

Holding face 82, as shown in Fig. 12D engages behind pin 84, which has ridden over the sloped shoulder leading to face 82, at the time of, or immediately before, severing of the wire is effected, while end face 83 engages behind pin 84 when the crank has completed a revolution.

In order to hold a flower against the end of the tube 62 and rod 65, an axially slideable rod 85 is mounted in guides 86, 87 brazed or otherwise secured to tube 62, and a guide 88 attached to side wall 22 of the frame. A head 89 is mounted on the forward end of the rod 85 by a set screw 90, and a pair of fingers 91 are secured in the head 89 in any suitable manner. The fingers 91 are bent as shown in Fig. 3 so as to firmly grip the calyx 91a of a flower 91b when the fingers are drawn toward the end of the tube and rod which function is performed by a coil spring 92 mounted on the rod 85 with its forward end bearing against a threaded sleeve 93 screwed into guide 86 and an abutment collar 94 secured to the rod by a set screw 95. Spring 92 is under compression and therefore normally holds collar 94 against guide 87.

Rod 85 is moved forwardly by a small detent block 96 secured to the rearward end of the rod 85 by set screws 97. The rearward end of the block is vertically slotted and a combined thumb piece and detent 98 (Fig. 11) is pivoted in the slot on a pin 99 extending across the slot. The thumb piece 98 is provided with an upward extension 100 for engagement by the operator's

thumb, and with a downwardly and rearwardly extending pawl part 101. The piece is freely swingable on said pin 99 within a limited range of movement determined by the engagement of the rear face 102 of the piece with the end of the slot and is pivoted off center on pin 99 so that it is normally held by gravity with pawl part 101 in position to be engaged by a pin 103 projecting inwardly from the crank 52, but when the upward extension 100 is rotated slightly forward by the thumb of the operator, pawl part 101 is moved out of the path of pin 103.

The operator pushes on the upward extension 100 to push the rod 85 forward to move fingers 91 outwardly to position a flower and also to enable crank 52 to be swung clockwise to operate the device, while at the termination of an operative revolution by the crank, the pin 103 will again move rod 85 forward to release the flower.

The operation of the device is as follows, and the position of the crank and parts mounted on the outer face of the frame and operated by the crank and cooperating therewith are shown in the successive diagrams of Fig. 12 and indicated A through E.

In the starting position with all parts at rest, the spring 92 is holding pawl piece 101 against pin 103 projecting from the crank 52, and is therefore holding pin 84 projecting from the crank against stop face 83. Crank 52 is therefore resiliently held against clockwise rotation by spring 92 and is positively held against any counter-clockwise movement. This position is shown in 12A. At this time shearing arm 72 is still raised since pin 75 projecting from the crank arm is engaged under the lowest point of cranked lever 76, and blossom holding fingers 91 are drawn close toward the outer end of tube 65.

In the first operating movement, the operator takes hold of the handle with his right hand and with his thumb pushes thumb piece 100 of the detent block forwardly until stopped by guide 88. The movement of the rod 85 on which the detent block is mounted moves the blossom holding fingers 91 away from the end of tube 62 and the operator inserts a flower, for example, the partly open rose 91b, with its calyx 91a located between the fingers and the end of the tube. This position of the parts is shown in Fig. 12B.

The operator next relaxes pressure against spring 92 with thumb piece 100 still elevated causing detent block 96 to move from position shown in 12B to 12C as indicated by the directional arrow in the latter view, whereupon spring 92 will hold the calyx against the end of the tube 62 and pawl piece 101 will be permitted to fall by gravity to be in position to engage with pin 103 when the crank has been turned nearly a full circle.

The next stage of the operation is shown in Fig. 12D wherein the crank has been turned slightly further, releasing pin 75 from lever 76, the end 76a of which is pulled downwardly by spring 68, thus bringing channel 67 and hole in hardened steel bushing 57 again into registry.

The slight movement forward of the crank necessary to release arm 76 does not cause any advancement of the wire, since wheel 30 is permitted to non-grippingly roll over wire 27 due to slight pressure against it caused by the regulated pressure by spring 39, at the time.

The position of the detent block 96 and of the cranked lever 76 which is drawn against stop 78 by spring 68, remain unchanged until the pin 75 again engages with the cranked lever and

raises it toward its upper position until it engages under shearing arm 72 at which time pin 84 on crank 52 passes over the shoulder on detent 80 and will engage face 82 if rotated counterclockwise. The face 82 is merely provided to insure that the operator cannot accidentally rotate the crank slightly further and then allow it to reverse, such a movement would cause the shearing arm to shear through the wire while the reverse movement of the crank, however small, would pull the slightly mutilated wire at the face of the cut into the hardened steel insert in which it would jam and prevent the next forward feeding movement of the wire to take place.

The completion of the operative cycle is shown in Fig. 12E in which it will be noted that the crank arm pin 103 has engaged the detent block pawl 101 and pushed the block and rod 85 longitudinally to release the blossom or flower. During the first portion of this movement the shearing arm has been moved upwardly a slight distance which causes shearing of the wire and registration of the groove 61 in rod 65 with the alined slots in tube 62 and tubular extension 59a of housing 59, so that the flower or blossom may be removed with a length of wire which has been thrust through the calyx of the blossom and extends to about the same distance on each side. This process may be and is usually repeated on the flower which is turned through an angle of ninety degrees to furnish it with a second wire, the wires then being bent downward and twisted together to furnish a strong wire stem in the looped portion of which the flower or blossom is securely held.

If for any reason a short length of wire is required, as for instance to wire the stems of several flowers together, the operator merely stops the action of the feeding roller 30 by raising frame 31 after sufficient wire has been drawn from the supply spool, but the crank arm is kept on turning to cut off the length of wire chosen and let it drop from the machine.

While I have particularly described a preferred embodiment of my invention as now reduced to practice, nevertheless it is to be understood that changes and modification of the described embodiment may be made by those skilled in the art without departing from the scope of the invention as defined by the appended claims.

I claim:

1. A machine for forcing lengths of wire through objects such as flowers, comprising: a frame, an object holding member carried by said frame, means connected with said object holding member to move said member with respect to said frame, a wire supply spool carried by said frame, a pair of wire feeding rollers mounted in the frame to draw wire from the supply spool and force it forwardly, a fixed pivot carried by said frame on which one of said feed rollers is mounted, a pivotally mounted support mounted on said frame on which the other feed roller is mounted, resilient means effective to urge said pivotally mounted feed roller support and the feed roller mounted thereon toward the other feed roller of the pair, a member carried by said frame and positioned to guide the wire from the feeding rollers outwardly of the frame, an elongated member extending outwardly from said frame and having a longitudinal channel therein open at each end and adapted to receive wire from said member which guides the wire out of the frame and then support said wire while it is forced by said feeding rollers through its outer end into and through one of the aforesaid objects, means effective to sever the wire between the frame and said longitudinally extending member after a predetermined length of wire has been drawn from said supply spool, an object holding member carried movably by said frame and effective to hold an object through which wire is to be forced while such object is pressed against the outer end of said longitudinally extending member, and operating means effective to positively rotate said feed rollers one

is forced by said feeding rollers through its outer end into and through one of the aforesaid objects that is held by said object holding member, and said object holding member moving means operable to move said holding member toward one end of said longitudinal channel, means effective to sever the wire between the frame and said longitudinally extending member after a predetermined length of wire has been drawn from said supply spool, and operative means carried by said frame effective to positively rotate said feed rollers and to automatically operate said wire severing means.

2. A machine for forcing lengths of wire through objects such as flowers, comprising: a frame, an object holding member carried by said frame, a wire supply spool carried by said frame, a pair of wire feeding rollers mounted in the frame to draw wire from said supply spool and force it forwardly, a hardened member having a hole drilled therethrough closely fitting the wire and effective to guide the wire from the feeding rollers outwardly of the frame, a wire support mounted on said frame, a longitudinally extending member mounted for rotation relatively to said wire support, and having a longitudinal groove therein open at each end and adapted to receive wire from the member guiding the wire out of the frame, said groove being covered by the wire support while the wire is being forced through its forward end into the object by the feed rollers, and supporting the wire, means effective to sever the wire between the frame and the longitudinally extending member after a predetermined length of wire has been drawn from the supply spool, and operating means effective to rotate said feed rollers and to automatically operate the means effective to sever the wire, and to rotate said longitudinally extending member to free the groove therein from coverage by the wire support immediately after the wire has been severed.

3. A machine as set forth in claim 2 and in which said wire support mounted on said frame comprises a tube having a longitudinally extending slot therein and said longitudinally extending member comprises a rod mounted for oscillatory motion about its axis in said tube with the longitudinally extending groove therein normally held out of registration with said slot.

4. A machine for forcing lengths of wire through objects such as flowers, comprising: a frame, a wire supply spool carried by said frame, a pair of wire feed rollers mounted in the frame to draw wire from said supply spool and force it forwardly, a member carried by said frame and positioned to guide the wire from the feeding rollers outwardly of the frame, an elongated member extending outwardly from said frame and having a longitudinal channel therein open at each end and adapted to receive wire from said member which guides the wire out of the frame and then support said wire while it is forced by said feeding rollers through its outer end into and through one of the aforesaid objects, means effective to sever the wire between the frame and said longitudinally extending member after a predetermined length of wire has been drawn from said supply spool, an object holding member carried movably by said frame and effective to hold an object through which wire is to be forced while such object is pressed against the outer end of said longitudinally extending member, and operating means effective to positively rotate said feed rollers one

revolution in each operative cycle of the machine, and to automatically operate said means effective to sever the wire, and to move the object holding member to release the object after operation of the means severing the wire has been effected.

5. A machine as set forth in claim 4 and in which said operating means include: a crank rotatably mounted on the frame, and detent means effective to prevent reverse rotation of said rotatable crank.

6. A machine as set forth in claim 4 and in which said operating means comprises: a crank rotatably mounted on the frame, detent means effective to prevent reverse rotation of said rotatable crank, an arm effective to operate the means severing the wire, a lever to actuate said arm, and pins projecting from said crank and engaging the arm effective to operate the wire severing means, and the object holding means to move the latter to release position at the end of each operative revolution of said crank.

7. A machine for forcing wire through the base portion of flowers comprising: a frame having one side closed, a wire supply spool rotatably mounted upon said frame, a pair of wire feed rollers mounted on said frame, a hardened member drilled with a hole for the passage and guidance of wire fed by the feed rollers, a tubular support mounted upon said frame to project longitudinally therefrom, a rod mounted within said tubular support, said rod being rockable about its axis and having a longitudinal groove open at each end and normally axially aligned with the hole in said hardened member to receive wire projected through said hardened member by the feed rollers for passage through the groove in the rod, said wire being enclosed between the walls of the groove and the inner surface of said tubular support for projection beyond the outer end of the tubular support and rod into and through the flower, an arm secured to said rod effective when operated to rotate said rod partially about its longitudinal axis to sever the wire passing from the hardened member into the groove in said rod, a shaft rotatably mounted on the closed side of the frame, co-operating gears mounted on said shaft and on said feed rollers, a crank mounted on said shaft externally

5

of said frame whereby said shaft may be rotated to drive said feed rollers, a pin projecting from said crank, a lever pivotally mounted at one end on the aforesaid closed side of the frame and having its free end positioned to operate said arm secured to said grooved rod, a part on said lever being arranged to be engaged by the pin projecting from the crank toward the end of each operative revolution of the crank, and a spring operative to normally hold said arm and lever in inoperative position.

10 8. A machine as set forth in claim 7 and in addition comprising a rod mounted for longitudinal movement on said closed side of the frame and on the tubular support, flower holding fingers mounted at the end of the rod beyond and adjacent the end of the rod mounted within the tubular support, a detent block mounted at the opposite end of the longitudinally mounted rod, a pawl pivotally mounted in the detent block and a pin projecting from the crank in position to engage the detent, and a spring effective to urge the flower holding fingers toward the end of the tubular support whereby the flower holding fingers may be moved outwardly by the engagement of the pin projecting from the crank with the pawl carried by the detent block, and the crank may be released for rotation by moving the pawl out of the path of the pin projecting from the crank.

15 9. The machine of claim 2 and; means operatively connected with said object holding member for moving said object holding member toward one of said open ends of said longitudinal groove in order to position the object therein with respect to said groove.

CHARLES M. ANDERSEN.
